[57] **CLAIM**

The ornamental design for a boom clamp, as shown and described.

DESCRIPTION

FIG. 1 is a perspective view of a boom clamp showing my new design, the broken line showing of the microphone stand and boom is for illustrative purposes only and forms no part of the claimed design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a bottom plan view thereof;

FIG. 8 is a top plan view of an alternate embodiment of that shown in FIG. 1;

FIG. 9 is a front elevation view of FIG. 8;

FIG. 10 is a top plan view of an alternate embodiment of that shown in FIG. 1; and,

FIG. 11 is a front elevation view of FIG. 10.

The side views not shown of the alternate embodiments are the same as those of the first embodiment.

FIG. 2.

FIG. 5.

FIG. 4.

FIG. 6.

FIG. 7.

FIG. 8.FIG. 9.FIG. 10.FIG. 11.
